UNITED STATES PATENT OFFICE.

ROBERT E. HUNN, OF OAKLAND, CALIFORNIA.

TILE-PRESS.

1,205,636.

Specification of Letters Patent. Patented Nov. 21, 1916.

Application filed March 18, 1916. Serial No. 83,792.

To all whom it may concern:

Be it known that I, ROBERT E. HUNN, a citizen of the United States, residing at Oakland, in the county of Alameda and State of California, have invented new and useful Improvements in Tile-Presses, of which the following is a specification.

This invention relates to tile presses; and has for its object to form ornamental impressions on the faces of hollow tiles.

Heretofore hollow tiles have not been used for ornamental or decorative purposes, owing to the difficulty of applying pressure to the faces thereof to form ornaments without crushing or deforming the cross webs and end walls of the tile. To properly impress an ornament thereon the work must be done while the tile is in a comparatively fresh or green state, at which time it is exceedingly frangible and liable to crumble if pressure be applied unevenly to the surfaces thereof.

In carrying out the foregoing object, I employ an adjustable templet to receive a fresh tile of variable size, fingers coöperating therewith and movable into position within the cavities in the tile and expandable therein to provide supports for the walls of the cavities, and an impression member movable against the face of the tile to form the desired ornamental scroll thereon.

One form which my invention may assume is exemplified in the following description and illustrated in the accompanying drawings, in which—

Figure 1 shows a front elevation of a device embodying my invention. Fig. 2 shows a vertical, sectional view, taken on the line 2—2 of Fig. 3, illustrating the parts in operative position with a tile in place and showing the parts adjusted to receive a smaller tile than in the case of Fig. 1. Fig. 3 shows a vertical, sectional view, taken on the line 3—3 of Fig. 1, illustrating the extreme position of movement of the parts by solid and dotted lines. Fig. 4 shows a plan view of the device, with a portion of the cover broken away for the sake of clearness. Fig. 5 shows a side elevation of a hollow building tile, illustrating an ornamental depression thereon formed by the present device.

Referring in detail to the form of the invention illustrated herewith, I have shown a frame 10, of suitable shape and size, provided with a templet at its upper surface

formed of hinged end walls 11 and a hinged cover 12 carried on a rear extension 13 and having interlocking connections to compel them to open and close in unison. The interlocking connections comprise a cam 14, 60 carried on each end of the cover, and a lug 15 on the adjacent end wall working in a groove in said cam.

Carried within the frame 10 are a series of vertically movable, split fingers 16, loosely 65 carried upon spindles or ledges 17 formed upon a base 18. Lying between the split sides of each finger and working in grooves therein is a wedge-shaped expanding member 19 fixed upon a head 20, the latter slideable up and down on the spindles 17 and normally supported by the base 18. A handle 21, rigidly connected to the head 20 and projecting through a slot at the back of the frame, is moved by the operator to raise the 70 head and wedges.

Cords 23, attached to the base 18, working over pulleys 24 and provided with counterbalancing weights 25, serve to elevate the base and fingers in unison with the vertical 80 movement of the head 20 and wedges, on account of a portion of the load having been relieved therefrom. Recesses or slots 26, formed in the cover 12, register with the fingers and provide lateral supports therefor 85 when the same are raised to operative position projecting through the cavities 27 in a building tile 28. At this point the fingers have reached their upward limit of movement; whereupon further movement of the 90 handle 21 raises the wedges and causes expansion of the fingers within the cavities. The number of fingers employed corresponds to the number of cavities in the tile, and these, being removably mounted on the 95 spindles 17, may be varied to suit different numbers of cavities.

At the back of the templet is an impression plate 29 normally retracted against adjusting screws 29^a by means of springs 30. 100 The impression plate has a pair of rollers 31 on its rear surface projecting through openings in the extension 13, each of said rollers being adapted to be engaged by an eccentric head 32 formed on a lever 33 pivoted at 34 to the part 13. The face of the plate 29 is provided with an ornamental panel 35 of any suitable pattern.

In the operation of this device, with the impression plate retracted and the support 110

ing fingers lowered, as shown in Fig. 1, the operator raises the cover 12 which opens the end wings and permits the insertion of a freshly molded hollow tile in the templet. 5 The cavities in the tile are positioned to register with the fingers and thereupon the handle 21 is raised, which movement relieves a portion of the weight from the base 18 allowing the latter to be elevated by the counterbalancing weights 25 as the said handle is moved upwardly. The upward movement of the fingers 16 continues until they have passed through the cavities in the tile and enter the slots or recesses in the cover, and 15 thereafter the upward movement of the handle 21 causes the expanding wedges 19 to be moved relatively within the said fingers, thrusting them laterally into engagement with the walls of the cavity or faces of the cross webs. In such position the expanded fingers prevent crushing or deforming of the cross webs.

The cover 12, preferably, is provided with springs to insure its closure and also that 25 of the ends, and the said cover and ends, when closed, act to support the top surface and end walls of the tile on which, however, little or no outward pressure is applied. Still maintaining the handle 21 in raised 30 position the operator moves the levers 33 upwardly, thereby forcing the impression plate inwardly against the face of the tile, applying as much pressure as is necessary to form the desired ornament. The eccentric 35 levers permit the application of several hundred pounds pressure against the tile without undue exertion on the part of the operator. The tile being supported on the inside surfaces of its front wall and the cross webs between opposite walls being firmly gripped between the expanded fingers no crushing or deforming of the green tile can occur when pressure is applied to the outside face thereof.

40 Upon releasing the levers and the handle the parts will automatically return to inoperative position, and by having two levers 33, one adjacent to each end of the impression plate, the operator can release the pressure on the opposite sides of the plate in an uneven manner to permit the gradual entrance of air to the impression surface as is necessary in order to obtain a neat finish of the ornamentation.

45 Ordinary building tiles when neatly ornamented in this manner may be used for all decorative and finishing purposes where faced terra-cotta and other expensive material is now employed.

50 Many changes in the construction and arrangement of the several parts of the device herein illustrated and described may be employed without departing from the spirit of my invention as disclosed in the appended 65 claims.

The end walls 11, cover 12 and impression member 29, comprising the templet, together with the rear extension 13 to which they are secured, are detachably connected to the frame 10 by means of lugs and bolts 37, so that they may be quickly removed or replaced by a templet of a different size, whereby to provide for the reception of various sized tiles.

The number of supporting fingers 16 is 75 readily varied to suit the number of cavities in the different sized tiles.

Having thus described my invention, what I claim and desire to secure by Letters Patent is—

1. In a device of the character described, the combination of means to receive and support a hollow tile, and means to form an impression on the face thereof.

2. In a device of the character described, 85 the combination of means to receive a hollow tile, means to support the same at the walls of its cavities, and means to form an impression on one side thereof.

3. A device for forming impressions on 90 hollow tiles, comprising means movable into the cavities of the tile and expandable therein to engage and support the walls thereof, and an impression member movable against the face of the tile to form an ornament 95 thereon.

4. A device for forming impressions on 100 hollow tiles, comprising a templet having hinged ends and a cover to receive a hollow tile, expandable supporting members movable into the cavities of the tile to support the walls thereof, and an impression member 105 movable against the face of the tile.

5. A device for forming impressions on 110 hollow tiles, comprising a templet removable and replaceable to receive various sized tiles, a plurality of expandable supporting members movable into the cavities in the tile and adjustable to provide for varying numbers of cavities, and an impression member movable against the face of the tile.

6. In a device for forming impressions on 115 hollow tiles, comprising a templet, fingers movable vertically therein, means for operating said fingers, expanding wedges for said fingers, separate operating means for said wedges whereby to expand the fingers after the latter have entered the cavities in the tile, and an impression member on one side of the templet movable in and out.

7. A device for forming impressions on 120 hollow tiles, comprising a templet, split fingers carried on a base, weighted means for lifting said base to project the fingers through said templet, expanded wedges between the split sides of said fingers carried on a head relatively movable on said base, a handle for operating said wedges to expand the fingers after the latter have entered the cavities in a hollow tile, and an impression 125 member movable against the face of the tile.

member movable against the face of a tile when the latter is in position within the templet.

8. A device for forming impressions on hollow tiles, comprising a templet, expandible supporting members coöperating therewith to enter the cavities in a tile, an impression plate for said templet, and means for moving said plate against the tile to impress an ornament thereon, said means being operable to release the plate unevenly at its opposite ends to admit air gradually to the face of the tile.

9. A device for forming impressions on hollow tiles, comprising a templet, expandible supporting members coöperating therewith to enter the cavities in a tile, an impression plate for said templet, and an ec-

centric lever at each end of the impression plate for moving the same against a tile to 20 impress an ornament thereon.

10. A device for forming impressions on hollow tiles, comprising adjustable means to receive tiles of various sizes, means adjustable in numbers to support said tiles at 25 the walls of their cavities, and an impression member movable against the face of the tile to form an ornament thereon.

In testimony whereof I have hereunto set my hand in the presence of two subscribing 30 witnesses.

ROBERT E. HUNN.
